UNITED STATES PATENT OFFICE.

MARTIN W. CARR, OF SOMERVILLE, MASSACHUSETTS.

DESIGN FOR A VASE.

SPECIFICATION forming part of Design No. 17,628, dated August 16, 1887.

Application filed May 12, 1887. Serial No. 237,999. Term of patent 3½ years.

To all whom it may concern:

Be it known that I, MARTIN W. CARR, a citizen of the United States, residing at Somerville, in the county of Middlesex, State of Massachusetts, have invented and produced a new and original Design for Vases or Bouquet-Holders, of which the following is a full, clear, and exact description, reference being had to the accompanying drawing, forming a part of this specification, in which the figure is an isometrical perspective view representing my newly-designed vase.

The leading features of my design consist in the base A, standard or support *x*, and holder C. The base is in imitation of a broad leaf or "lily-pad," having its surface marked or lined to represent a mid-rib and veins. The holder C is in imitation of the flower of a calla-lily plant, and is represented as standing vertically over the center of the leaf A, the curved support *x* in imitation of the stalk of

the calla-lily plant, its upper end extending upward to the base of said holder and its lower end being shown as passing under and concealed by the blade of said leaf. The handle B. of the vase is in imitation of the petiole or stem of the leaf coiled, as shown.

Having thus explained my design, what I claim is—

The design for a vase or bouquet-holder herein shown and described, consisting of a base in imitation of a leaf, a holder in imitation of the flower of a calla-lily plant, a curved support in imitation of the stalk of said flower, the upper end of said support extending to the base of said holder above said leaf, and a handle in imitation of a coiled petiole or stem of the leaf, substantially as described.

MARTIN W. CARR.
